(57) **CLAIM**

The ornamental design for an artificial tendon, as shown and described.

DESCRIPTION

FIG. 1 is a perspective view of an artificial tendon; FIG. 2 is a top plan view thereof; FIG. 3 is a front view thereof; FIG. 4 is a right side view thereof; and, FIG. 5 is a cross-sectional view taken along line 5-5 in FIG. 3.

It is noted that a bottom plan view of the artificial tendon is identical to the top plan view of FIG. 2, a rear view of the artificial tendon is identical to the front view of FIG. 3, and a left side view of the artificial tendon is identical to the right side view of FIG. 4.

1 Claim, 4 Drawing Sheets

FIG. 1

FIG. 2

FIG. 3

FIG. 4

FIG. 5
